UNITED STATES PATENT OFFICE.

ARTHUR J. BAZELEY, OF CLEVELAND, OHIO, ASSIGNOR TO THE NATIONAL MALLEABLE CASTINGS COMPANY, OF CLEVELAND, OHIO, A CORPORATION OF OHIO.

CAR-COUPING.

1,072,075.

Specification of Letters Patent.

Patented Sept. 2, 1913.

Application filed July 3, 1908. Serial No. 441,797.

To all whom it may concern:

Be it known that I, ARTHUR J. BAZELEY, a citizen of the United States, and a resident of Cleveland, Cuyahoga county, Ohio, have 5 invented a new and useful Car-Coupler, of which the following is a full, clear, and exact description, reference being had to the accompanying drawings, forming part of this specification, in which—

10 Figure 1 is a front elevation of a car coupler constructed in accordance with my invention, and provided with a lock-lifting mechanism operated from above; Fig. 2 is a vertical longitudinal section of the coupler; Fig. 3 is a detail side elevation; and Fig. 4 an edge view of the lifting link; Figs. 15 5 and 6 are similar views of the locking device for the lock; Fig. 7 is a detail view of the lock; and Fig. 8 is a vertical cross section through the coupler head showing the 20 attachment of the parts to the lock.

Referring to the top opening coupler shown in Figs. 1 to 8, 2 represents the coupler head and 3 is the knuckle of the coupler; and 4 is the locking and opening piece of the coupler, which is preferably of angled form, as shown in detail in Fig. 7, having a locking-head 4' and a member 4^a which fits back of the tail of the knuckle and is adapted to open the same. The locking and opening piece has also an intermediate member having preferably a notch or recess 4^b adapted to engage the head of the coupler and to tip thereon for the purpose of swinging the 35 knuckle open, as illustrated in Fig. 8. The lower link 5 of the lifting chain is connected with an eye 6 formed on or cast integral with the top of the locking member 4' and this link 5 has at its upper end an elongated 40 hole 5^a, a forward projection 5^b and a rear projection 5^c. Between these is an intermediate recess 5^d.

The upper link 7 of the chain within the coupler head is preferably of fork or clevis form, and is attached to the lower link by means of a pin 7^e secured with a suitable cotter. This link has a recess between two vertical walls 7^a and 7^b divided by an intermediate rib 7^c and at the top of the link 7 is an eye 7^d through which extends the arm of the uncoupling rod 8. The link 7 extends through a hole at the top of the coupler head and is preferably made larger at its upper portion, of suitable size to fill this hole

when the link is in its lowermost position so 55 as to exclude dirt from the coupler.

When it is desired to lift the lock, the lifting rod 8 is operated by means of a lever handle 9 so as to lift the links 7 and 5, the link 5 fitting within the fork of the link 7 60 and being held thereto by a pin 7^e which passes through the elongated hole 5^a. The lifting of the links pulls them into alignment and draws the link 5 into line with the hole in the coupler head and enables it to pass 65 freely through the hole. When, however, the lifting rod is released so as to permit the links and the lock to descend, the elongated hole 5^a will permit the pin 7^e to drop downwardly with the link 7, so that the wall 7^b 70 of the link 7 will engage the link 5 at the top of the projection 5^c, and as this point of engagement is back of the attachment of the link 5 to the lock at 6, the link 5 will be caused to move backward at its upper 75 end so as to bring the inner side of the projection 5^b into engagement with the middle rib 7^c, thus holding the link 5 from further backward movement. The projection 5^c, being thus brought beneath the upper wall of 80 the coupler head, is held positively from rising, and any tendency of the lock to jump or creep upwardly is resisted. It, however, does not prevent the free lifting of the links and of the lock, for as soon as the link 7 is 85 lifted it will draw the link 5 into alignment with it and thus free the projection 5^c from engagement with the coupler head, taking it out of the path thereof. As the middle rib 7^c of the link 7 is between the projections 5^b 90 and 5^c of the lower link, the movement of the two links relatively to one another is limited and the upper link is kept in a substantially upright position when the lock is raised.

95

This device may be modified by applying it to locks of other descriptions, and it may be operated by lifting mechanism other than the kind shown in the Fig. 1 of the drawings.

100

I claim:

1. A coupler having a swinging knuckle, a lock engaging the knuckle and movable independently of the knuckle, the top of the lock being below the top wall of the coupler 105 cavity, leaving a space between said wall and lock when the knuckle is locked, and a lock lifting device comprising a plurality of

jointed members extending through the space in the upper part of the head and through a hole in the top wall of the coupler head, said members being arranged to cause the lower member to move laterally by gravity under a stop shoulder on the coupler head to prevent creeping of the lock, and the upper member having an enlargement arranged to seat against the rim of the top hole in the coupler head when the knuckle is locked, the jointed members having a slotted connection and being angled therein and the lower member being held in an inclined position to engage the stop on the coupler head, said members also having co-acting portions which limit their angular movement in both directions.

2. In a car coupler, a lifting link adapted to have a locking engagement with the upper wall of a coupler head, a clevis pivoted to said link and having a slot to receive the upper portion of the link, said slot having a stop portion, and a shoulder on the link arranged to be engaged by said stop to limit the backward movement of the upper end of the link under the upper wall of the coupler; substantially as described.

In testimony whereof, I have hereunto set my hand.

ARTHUR J. BAZELEY.
